(57) **CLAIM**

The ornamental design for a caddy, as shown and described.

DESCRIPTION

FIG. 1 is a perspective view of a caddy showing the design; FIG. 2 is a top perspective view showing the caddy of FIG. 1; FIG. 3 is a bottom perspective view of the caddy of FIG. 2; FIG. 4 is a side view of the caddy of FIG. 2; FIG. 5 is an end view of the caddy of FIG. 2; FIG. 6 is a top view of the caddy of FIG. 2; and, FIG. 7 is a bottom view of the caddy of FIG. 2.

The broken lines showing articles in a caddy are for the purposes of illustrating environment and form no part of the claimed design.
